INVENTOR

ALBERT EDWARDS.

BY

Sam Mather,

ATTORNEY

UNITED STATES PATENT OFFICE.

ALBERT EDWARDS, OF BRIDGEPORT, CONNECTICUT.

SANITARY RECEPTACLE.

Application filed March 29, 1924. Serial No. 702,762.

To all whom it may concern:

Be it known that I, ALBERT EDWARDS, a citizen of the United States, and a resident of Bridgeport, in the county of Fairfield and State of Connecticut, have invented certain new and useful Improvements in Sanitary Receptacles, of which the following is a specification.

This invention relates to an improved sanitary receptacle, and has for an object to provide a receptacle of this character adapted for use as a container for sugar, candy, doctors' and dentists' supplies, tobacco, and other such articles, which it is desired to maintain in a clean and sanitary enclosure, free from dust, dirt and vermin, and which at the same time will be quickly and conveniently accessible.

To this end it is proposed to provide, in the present embodiment of the invention, a receptacle having a counter-balanced cover adapted to be conveniently moved to open position, and which will automatically return to closed position, without effort or volition on the part of the user.

A further object is to provide a receptacle of extremely simple construction, attractive in appearance, and which is free of any structure or parts that can readily get out of order. Other objects are to provide an improved means for attaching the cover to a one piece bowl, of glass, crockery, or the like, and further to provide a cover which may be readily fixed in open position, when desired, as during filling.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of a sanitary receptacle, according to the present embodiment of the invention, and showing the cover in its normal closed position;

Fig. 2 is a side elevation of the same;

Fig. 3 is a vertical sectional view thereof;

Fig. 4 is a side elevation, showing the cover in fixed open position, and also indicating in dotted lines another open position, from which it is adapted to be returned to closed position;

Fig. 5 is a side elevation of a modified form of the invention;

Fig. 6 is a detail fragmentary view of the interlocking securing means for the cover supporting band employed;

Fig. 7 is a sectional view, taken along the line 7—7 of Fig. 6; and

Fig. 8 is a sectional view, taken along the line 8—8 of Fig. 6.

Similar reference characters indicate corresponding parts throughout the several figures of the drawings.

Referring to the drawings, the receptacle, according to the present embodiment of the invention, comprises a globular spherical bowl 10, open at its upper side, and having a flat base 11, and formed of any suitable material, depending upon the particular use to which it is to be put, as glass, porcelain, crockery, or the like. At its lateral equatorial line, the bowl is provided with an impressed annular recess 12, within which there is disposed a substantially flush cover supporting metal band 13, the ends of which are connected by an interlocking flush joint, consisting of a tongue 14 at one end, having a reduced neck portion, and interlockingly engaged in a correspondingly shaped cut-out 15 in the other end, the side walls 16 of the neck being slightly beveled, as shown in Fig. 8, and the engaging walls of the cut-out being swedged or forced over into locking relation therewith. This construction provides a neat flush structure, and greatly facilitates and economizes assembling.

The band 13 is provided at diametrically opposite points with projecting pivot screws 17 and 18, riveted therein, and upon which the cover, presently to be described, is rotatably supported in a manner to be lowered into tight relation with the edge of the bowl opening in the closed position, and to be raised slightly upon rotation in either direction to permit of the free movement of the cover about the sides of the bowl.

The cover comprises a top 19 in the form of a concavo-convex spherical segment, of greater diameter than the bowl, and adapted to cover the opening with its edges projected slightly below the edge of the opening, the inner surface of the cover, in the closed position thereof, resting upon the edge of the opening of the bowl, so as to render it air-tight and dust-proof. At each side of the top there are provided downwardly extending side arms 20 and 21, in continuation of the spherical curvature of the top, and disposed in slightly spaced relation to the

upper hemisphere of the bowl, and depending below the band 13 in diverging relation to the lower hemi-sphere; being provided with substantially pear-shaped apertures 22 in alignment with the pivot screws 17 and 18. Pear-shaped flanged camming pivots 23 are secured upon the respective pivot screws, being fixed against rotation by soldering or the like, and are engaged by the 10 apertures 22 of the side arms, the resiliency of the arms and the flanges of the pivots retaining the arms in place, and at the same time permitting the cover to be readily disengaged, when desired for cleaning, or the 15 like, the apertures being of such size as to slip over the flanges. In the closed position of the cover the points of the apertures 22 engage the points of the pivots 23, so that the cover is lowered and engaged tightly 20 upon the edge of the opening of the bowl. Upon swinging movement of the cover to either side the camming pivots cause the cover to be immediately lifted, so that its inner surface is free from the surface of 25 the bowl, and it may therefor be freely swung to open position. As is clear from the drawings the sides of the camming pivots diverge gradually at each side of the point and merge into the lower semi-circular cross- 30 section portion; the apertures being of greater height and width than the pivots, and the width being just slightly greater than the height of the pivots. Upon rotation of the cover the inclined side of the aperture rides 35 over the point of the pivot, camming the cover to slightly raised position, and in which position the inner surface of the cover is concentric to and slightly spaced from the globular surface of the bowl. In the completely 40 open position, as shown in full lines in Fig. 4, the aperture is at right angles to the camming pivot, and the vertically disposed point and base of the pivot is snugly engaged by the transverse portion of the aperture 45 so that looseness is prevented, and the cover may be at the same time freely rotated. Upon closing the cover lowers into engagement with the edge of the opening, the frictional engagement upon coming to 50 such closed position preventing swinging of the cover.

At their lower ends the arms are apertured, as at 24, and have ball weights supported thereon, these weights each comprising hemi-spheres 25 and 26 secured at each side of the arms by means of a screw 27 in one of the halves engaged through the aperture 24 in a threaded socket 28 of the other. These weights may be of any suitable construction, and attached in any suitable manner, as will be obvious.

The cover is provided centrally with a handle 29 screwed thereon by means of a threaded shank 30, secured against removal 65 by peening over the inner end of the shank,

as at 31. Sufficient clearance is provided between the cover and the handle to allow the latter to be screwed inwardly, as shown in Fig. 4, to engage the end of the shank against the band 13, to thereby secure the cover in 70 open position.

The weights being heavier than the cover and disposed below the center of gravity, normally counter-balance and center the cover to maintain it in closed position, it 75 being only necessary, in order to obtain access to the bowl, to swing the cover to either side, as shown for instance in dotted lines in Fig. 4, the weights automatically returning 80 the same to closed position upon release.

In Fig. 5 I have illustrated a modified form of pivotal mounting for the cover consisting of a circular cross-section pin 32 secured to the band 13, and having a vertically disposed flattened head 33 projecting above 85 and below it, the pin being adapted to be engaged by an aperture 34 in the side arm of the cover having horizontally extended slot portions 35 adapted to pass over the head 33, in the lateral open position of the 90 cover, being locked in pivotal relation upon the pin in all other positions. Inasmuch as the arms of the cover are slightly resilient, this feature permits the cover to be readily removed, when desired, and greatly facilitates 95 the assembling of the device.

I have illustrated and described preferred and satisfactory embodiments of the invention, but it will be obvious that changes may be made therein, within the spirit and scope 100 thereof, as defined in the appended claims.

Having thus described my invention, what I claim and desire to secure by Letters Patent is:

1. A sanitary receptacle comprising a bowl 105 having an opening, a pivotally mounted cover having its inner surface contiguous to the edge of said opening and describing an arc about the pivotal axis of said cover, whereby it is adapted to be moved in one or the other directions from its medial closing position to a position to expose said opening, and being freely movable in its open position with respect to the edge of 110 said opening to its medial closing position, and means adapted to automatically return the same from its moved open position to its normal medial closing position upon release.

2. A sanitary receptacle comprising a 115 globular bowl having an opening in its upper side, a cover in the form of a concavo-convex spherical segment having side arms extending about each side of said bowl, means pivotally mounting said side arms upon said bowl upon a horizontal diametric axis thereof adapted to normally cover said opening and to be moved to a position to expose said opening, and weights at the lower ends of said side arms adapted to 120

maintain said cover in closed position and to automatically return the same to said closed position upon release.

3. A sanitary receptacle comprising a globular bowl having an opening in its upper side, a cover in the form of a concavo-convex spherical segment, pivotally mounted upon said bowl upon a horizontal diametric axis thereof adapted to normally cover said opening and to be moved to a position to expose said opening, counterbalance means for said cover adapted to automatically return the same to its covering position upon release, and a handle mounted centrally of said cover and adapted to be moved inwardly with respect thereto to lockingly engage the same with said bowl in the open position of said cover to retain the same in such open position.
4. A sanitary receptacle comprising a bowl having an opening, a pivotally mounted cover adapted to normally cover said opening and to be moved to a position to expose said opening, means adapted to automatically return the same to its normal covering position upon release, and means adapted to move said cover into and out of contacting relation with said bowl upon movement to closed and open positions respectively.
5. A sanitary receptacle comprising a bowl having an opening, a pivotally mounted cover adapted to normally cover said opening and to be moved to a position to expose said opening, means adapted to au-

tomatically return the same to its normal covering position upon release, and means adapted to move said cover into and out of tight engagement with the edge of said opening upon movement to closed and open positions respectively.

6. A sanitary receptacle comprising a bowl having an opening, a pivotal cover adapted to normally cover said opening and to be moved to a position to expose said opening, camming pivots supporting said cover, adapted to move said cover into and out of contacting relation with said bowl upon movement to closed and open positions respectively, and means adapted to automatically return said cover to its normal covering position upon release.

7. A sanitary receptacle comprising a globular bowl having an opening in its upper side, a pivotally mounted cover in the form of a concavo-convex spherical segment adapted to normally cover said opening and to be moved to a position to expose said opening, means adapted to automatically return said cover to its normal covering position upon release, and means adapted to move said cover into and out of tight closing relation with said opening upon movement to closed and open positions respectively.

Signed at Bridgeport, in the county of Fairfield, and State of Connecticut, this 25th day of March, 1924.

ALBERT EDWARDS.
